UNITED STATES PATENT OFFICE

EARL W. NEWTON, OF EVANSTON, ILLINOIS

DESIGN FOR A GOBLET OR SIMILAR ARTICLE

Application filed November 23, 1931. Serial No. 41,826. Term of patent 14 years.

To all whom it may concern:

Be it known that I, EARL W. NEWTON, a citizen of the United States, residing at Evanston, in the county of Cook and State of Illinois, have invented a new, original, and ornamental Design for a Goblet or Similar Article, of which the following is a specification, reference being had to the accompanying drawings, forming a part thereof, where-

Fig. 1 is a perspective view of a goblet showing my new design;

Fig. 2 is a diametrical section of the same.

What I claim is:

The ornamental design for a goblet or similar article, as shown.

In testimony whereof I affix my signature.

EARL W. NEWTON.
